UNITED STATES PATENT OFFICE.

JOSHUA R. KING, OF NEW HAVEN, AND WILLIAM O. KING, OF SIDNEY, NEW YORK.

SPREADER FOR DRY MATERIALS.

1,205,221.

Specification of Letters Patent. Patented Nov. 21, 1916.

Application filed April 5, 1916. Serial No. 89,194.

To all whom it may concern:

Be it known that we, JOSHUA R. KING and WILLIAM O. KING, citizens of the United States, residing, respectively, at New Haven, in the county of Oswego and State of New York, and Sidney, in the county of Delaware and State of New York, have invented a new and useful Spreader for Dry Materials, of which the following is a specification.

The present invention relates to an improved machine for distributing and spreading dry materials, such as pulverized and granular materials, including crushed stone, lime, and other fertilizers, and the like.

An object of this invention is to provide a spreader of this character which is of simple and light construction and provided with a revolving drum-shaped body having adjustable outlets therethrough to distribute the material in a layer of the desired thickness as the body revolves; and which has means for adjusting these outlets without removing the material from the body, and without the necessity of overcoming the pressure of the weight of the material.

Another object of the invention is to provide a spreader of this nature with means for insuring the even distribution of the material entirely across the path of the machine, whether the machine is on level land, or whether it is traveling along the side of a hill.

A still further object of the invention is to provide an improved adjusting mechanism which is adapted to revolve with the body of the machine, and which simultaneously adjusts a plurality of outlets and securely holds all of the same when adjusted, to thus uniformly feed or distribute the material from the machine.

Other objects and advantages of this invention will be brought out in the following specific disclosure of the present preferred embodiment of the invention, the same being illustrated in the accompanying drawings, wherein—

Figure 1 is a top plan view of a spreader constructed according to this invention. Fig. 2 is a longitudinal central sectional view, taken vertically through the machine, the shutters being closed. Fig. 3 is a transverse central sectional view, taken through the machine. Fig. 4, is an enlarged, frag-

mentary sectional view, through the central portion of the machine, showing a portion of the door and the adjusting device thereon holding the shutters in open position. Fig. 5 is a top plan view, enlarged and partly in section, of one of the adjusting devices. Fig. 6 is an enlarged fragmentary perspective view, of a portion of the drum-shaped body of the machine, showing the shutters closed.

Referring to these drawings, wherein like parts are designated by similar numerals of reference throughout the several views, 10 designates an axle upon the opposite ends of which are mounted traction wheels 11, one of which at least is fixed to the axle 10, 70 as by a key 12, shown in Figs. 1 and 3.

The body of the machine is in the form of a drum or cylinder, and comprises the opposite ends or heads 13, a plurality of circumferentially spaced apart slats 14 and 75 interposed adjustable shutters 15. The heads 13 are in the form of disks having central openings therethrough for the reception of the axle 10 and having clamping plates 16 secured, by bolts 17, or the like, 80 against the outer faces of the heads 13 and about the axle 10. Bushings 18 are carried in the clamping plates 16 and have flanges 19 counter-sunk in the inner faces of the plates 16 and adapted to be securely clamped 85 from turning between the heads 13 and the plates 16. The bushings 18 bind on the axle 10, to turn therewith, so as to turn the drum-shaped body with the axle.

The outer ends of the bushings 18 are 90 mounted to turn in side bars 20 which are enlarged and apertured intermediate their ends to receive the bushings 18 therethrough. End bars 21 join the side bars 20 to provide therewith a substantially horizontal frame 95 encircling the cylindrical body. A tongue 22 is carried on one end of the frame for drawing the machine. Spacing rings 23 are preferably interposed between the outer ends of the bushings 18 and the wheels 11 to 100 space the latter from the side bars 20 of the frame.

Each slat 14 of the drum-shaped body comprises a flat metal strip secured at its opposite ends to the peripheral edges of the heads 13, and having an outturned reinforcing flange 24 along one edge. The opposite edge of the strip 14 is offset inwardly from

the body of the strip to provide a hinge seat 25.

Each shutter 15 is composed of a single length of sheet metal having an outturned flange 26 on its outer edge, and having at its inner edge, and at its opposite ends, longitudinally extending projections 27, which are headed. These projections 27 and the inner edge of the shutter 15 are adapted to rest upon the hinge seat 25 of the slat. The hinge seats 25 carry staples 28 near their opposite ends for engagement over the headed projections 27 to hingedly connect the shutters 15 to the slats 14. There is thus a shutter 15 hinged on each slat. The slats 14 are counter-sunk in the peripheral edges of the heads 13, so as to close the body at the edges of the heads.

The body is provided with a central partition 29, which divides the body into two compartments, so that should the body be tilted, the material will not collect in one end of the body, and thus be unequally distributed across the path of the machine, but will be held in the opposite ends and caused to pass out of the openings, between the slats and the outer ends of the shutters, entirely across the machine. The partition 29 is preferably fixed to the axle, as by a key 30, to further secure the body to the axle.

The body is provided in one side with a door or hinged cover adapted to be opened to place material in the lateral compartments in the body. This door comprises a plurality of slats 14 and shutters 15 of the same construction and arrangement as the remaining slats in the body, with the exception that these door slats 14 are secured upon a frame composed of a pair of opposed strips 43, of metal or the like, counter-sunk in the peripheries of the opposed heads 13, each strip being substantially of the same width as its supporting head 13. These strips 43 are located at one side of the body and conform to the recesses therein. The slats 14 of the door section are secured flat against these frame strips, and the hinged slats 15 lie flat against the frame strips when the slats are closed. The door is secured at its inner edge by hinges 31 to the adjacent slat 14, the hinges being secured to the two adjacent slats 14 and to the heads 13 beneath the opposite ends of the slats. The free edge of the door section of the body is held closed in any suitable manner, such as by a finger 32, (Fig. 2) hinged upon one of the slats 14 adjacent the free edge of the door section. It will be noted from the drawings that the door section terminates at its hinged and free edges in slats 14, and that the body wall of the device terminates in fixed slats 14, so as to provide a suitable hinge connection for the door, and also a suitable support for the fastener 32, which is adapted to hold the door closed. The shutters 15 are adapted to be

swung, to more or less extent, outwardly from the outturned flanges 24 of the slats in order to increase or decrease the space therebetween and admit more or less of the contents of the body to pass outwardly through the openings. Adjusting and retaining means are provided for these shutters 15, and are connected to a plurality of the same, so as to operate them simultaneously. The adjusting and holding devices are shown in the present instance as three in number, spaced substantially equi-distantly about the body, one of the devices being mounted on the door to control all of the shutters 15 carried thereby. Each one of these adjusting and holding devices comprises a rigid band or strip 33 connected at one end to one of the slats 14 by means of links, 34, and passing peripherally across the desired number of the shutters 15. The band 33 has a hinged connection with each of the outturned flanges 26, the connection being shown in the present instance as comprising a substantially U-shaped bolt 35 threaded at its extremities, engaging at its intermediate portion through the flange 26, and projecting outwardly through the band 33. Binding nuts 36 are threaded upon the outer ends of the U-bolt and are turned up against a clamping plate 37, which lies against the outer side of the band 33. A bracket plate 38, in the form of an angle iron, has one flange thereof secured to a slat 14 lying intermediate the ends of the band 33. The outstanding flange of the bracket plate 38 has a slot 39 therethrough to receive and admit of the longitudinal and outward movements of the band 33. Fixed on the band 33 is an outstanding lug 40, spaced from the bracket plate 38 and provided with a vertically movable sleeve 41 in one side of which is swiveled the inner end of an adjusting screw 42.

To use the device, the finger 32 is turned out of engagement with the slat 14 on the outer end of the door. The door is now swung outwardly on the hinges 31. The body of the machine is so turned as to dispose the door at the top thereof. The material is now placed in preferably equal quantities in the end compartments or sections of the body. After the door is closed and it is desired to adjust the shutters 15 to regulate the amount of material distributed through the openings or slots in the body, the body is turned so as to bring the separate adjusting devices one at a time to the top of the body, so that the respective shutters of the adjusting devices may be adjusted into the desired position without the necessity of overcoming the pressure of the weight of the material against the shutters 15 at the lower side of the body.

In adjusting the shutters 15, the screw 42 is turned so as to draw the lug 40 toward the bracket 38 or toward and into the posi-

tion shown in Fig. 4. The lug 40 moves the band 33 circumferentially around the body toward the bracket 38. The band 33 swings upon the links 34 and moves away from the adjacent side of the body.

The sleeve 41, carried by the lug 40, remains in alinement with the adjusting screw 42 as the lug 40 is free to slide outwardly in the sleeve. The sleeve 41 is cut away at its 10 lower edge to receive the bore of the lug and admit a free adjustment of the lug and band within a wide range. Each one of the adjusting devices is of this construction and is operated in this manner. It is preferable to rotate the body as above described, so as to bring the shutter adjusting devices 15 one at a time to the top of the body.

When the desired adjustment of the shutters 15 is had, the machine is moved along 20 over the surface to rotate the drum-shaped body. This turning of the body tumbles and loosens the material therein and causes it to fall outwardly through the slots or openings between the shutters and the slats. 25 The partition 29 in the body insures an even distribution of the material from end to end of the body when the body is horizontal, and when it is tilted, as when being moved over the side of a hill.

30 What is claimed is:—

1. A spreader for dry material including a revoluble body having a series of transversely extending slots in its peripheral wall, a series of shutters extending transversely across the body for closing the slots, a connecting device attached to the shutters, and adjusting means engaging the connecting device to move the shutters substantially circumferentially of the body and open the 40 slots throughout their lengths.

2. A spreader for dry material including a revoluble body having peripheral slots therein, a plurality of adjustable shutters carried by the body for opening and closing 45 the slots, an exteriorly arranged band connected to the shutters, and screw actuated means for moving the band.

3. A spreader for dry material including a revoluble body having distributing slots 50 therein spaced apart about the entire periphery of the body, a controlling device for each slot, and a number of independent adjusting devices spaced peripherally around the body and connected to independent 55 groups of the controlling devices to adjust each group thereof separately.

4. A spreader for dry material including a cylindrical body adapted to be rotated and to contain the material, a plurality of adjustable shutters spaced peripherally about the body for controlling the distribution of the material from the body, a band arranged peripherally against the body and having connection with said shutters, and 60 means connected to the band to move the 65

same and adjust the shutters into the desired position, and to hold the band when adjusted.

5. A spreader for dry material including a cylindrical body adapted to be rotated and 70 to contain the material, a plurality of adjustable shutters spaced peripherally about the body for controlling the distribution of the material from the body, a plurality of bands arranged peripherally about the body 75 and having connection with independent groups of said shutters, and independent means for each band to move the band and adjust the shutters connected thereto into the desired position, and to hold the band 80 when adjusted.

6. A spreader for dry material including a revoluble cylindrical body adapted to contain the material and having longitudinally extending and peripherally spaced apart 85 slots in the wall thereof, and a plurality of shutters mounted on the body to control said slots, a peripherally extending band connecting the outer ends of the shutters, and means carried by the body and engaging 90 said band to move the same longitudinally and open and close the shutters, said means being adapted to hold the shutters from movement when adjusted.

7. A spreader for dry material including 95 a revoluble body having a plurality of longitudinally extending shutters hinged in the wall thereof, a band extending across and having connection with the shutters, and means for moving said band on the body to 100 simultaneously swing the shutters into various angles to open and close the wall of the body, said means being adapted to lock the band and the shutters in any adjusted position. 105

8. A spreader for dry material including a revoluble body composed of spaced apart heads, a plurality of slats rigidly secured at their opposite ends to the heads and being spaced peripherally thereabout, each slat 110 having a longitudinal outturned flange on one edge, a shutter hinged to each slat and adapted to close down upon the outturned flange of the next adjacent slat and having an outturned flange upon its outer end, and 115 means for moving the shutter away from said flange of said next adjacent slat.

9. A spreader for dry material including a revoluble body having spaced apart rigid slats, each slat having an outturned flange 120 along one edge and an inwardly offset flange along its opposite edge providing a hinge seat, shutters hinged at one edge upon said hinge seats of the slats and having outturned flanges at their opposite edges, said 125 shutters being adapted to rest upon the outturned flanges of the slats, means for connecting a plurality of the shutters together, and means for actuating said means to move the shutters on the hinges. 130

10. A spreader for dry material including spaced apart heads, spaced apart slats secured at their opposite ends to the heads, shutters hinged to the slats to close the spaces therebetween, a peripherally extending band mounted for longitudinal movement on the slats, a hinged connection between each shutter and said band, a bracket fixed to one of said slats, a lug on said band, and
13 an adjusting screw threaded through the bracket and having connection with said lug whereby the turning of said adjusting screw moves said lug toward and from the bracket to move the band longitudinally and
15 simultaneously swing said shutters.
11. A separator for dry material including a body having a plurality of hinged shutters in the wall thereof, a band traversing the shutters and having hinged connection therewith, a fixed bracket mounted on the body, a lug mounted on the band opposite the bracket, an adjusting screw threaded through the bracket, and a sleeve swiveled on the outer end of the screw and slidably
20 engaging over said lug, whereby the turning of the screw moves the lug toward and from the bracket to adjust said band and shutters.
12. A spreader for dry material including spaced heads, spaced apart slats secured to
25 the heads, a shutter hinged on each slat to close the openings between the slats, a band traversing the shutters and having hinged connection with the outer free edges thereof, a bracket fixed to one of said slats and extending radially outward therefrom and having a relatively large slot therein to receive the band therethrough, a lug fixed on the band in registry with the bracket, a sleeve surrounding the lug and adapted to
30 admit of the free radial movement of the lug in the sleeve, and an adjusting screw connecting the sleeve to the bracket and adapted to move the sleeve and lug toward
35
- 40

and from the bracket, and to move the band longitudinally and swing the shutters into 45 open and closed positions.

13. A spreader for dry material including a revoluble body composed of spaced apart heads, a plurality of slats rigidly secured in spaced apart relation at their opposite ends 50 to the heads and providing slots therebetween and having a longitudinal outturned flange along one edge, a series of movable shutters between each fixed slat for closing the slots, each shutter hinged at one edge to the adjacent edge of each slat and adapted to bear at its other edge upon said outturned flange to close the intervening slots, and means for moving the shutters toward and from said flanges to open and close the slots. 60

14. A spreader for dry material including a revoluble body composed of spaced apart heads, a plurality of slats rigidly secured in spaced apart relation at their opposite ends 65 to the heads and providing slots therebetween and having a longitudinal outturned flange along one edge, a shutter hinged to the opposite edge of each of said slats and adapted to extend across the intervening slots and engage said outturned flange, and 70 a band connected to said shutters and adapted to be shifted and to simultaneously actuate all of said shutters for opening and closing the slots.

In testimony, that we claim the foregoing 75 as our own, we have hereto affixed our signatures in the presence of two witnesses.
